TWO STAGE CONTROL INSTRUMENT

Gifford I. Holmes, Minneapolis, Minn., assignor
to Minneapolis-Honeywell Regulator Com-
pany, Minneapolis, Minn., a corporation of
Delaware

Application May 1, 1942, Serial No. 441,322

15 Claims. (Cl. 200—139)

This application is a continuation in part of my copending application Serial No. 301,900, filed October 30, 1939, as to all matter common to the two applications. The subject matter of these related applications and common to both, involves improvements in thermostatic devices.

The present invention relates to "Two stage control instruments," and more particularly to two stage instruments for summer and winter use.

In heating and cooling systems adapted to work under variable load conditions, it has been found that plural stage control is the most satisfactory, both from the standpoint of economy and comfort for the occupants. Many elaborate control systems, having a large number of control positions, have accordingly been devised to fill the need for modulating control. However, it has also been found that a simplified control having maximum and minimum load positions only will fill a large number of these needs satisfactorily. The two position control involves substantially decreased installation and upkeep costs, and hence has been generally accepted in the art.

A further need in the conditioning art is control of both heating and cooling for winter and summer, respectively. There are also times in the spring and fall when both heating and cooling may be needed from day to day. For this reason the need is felt for control means having automatic changeover from heating to cooling, and vice versa.

An object of this invention is to provide a plural stage control means having automatic changeover from heating to cooling control.

A further object is to provide a simple changeover switch embodying two stage control.

Another object is to provide a simple changeover switch embodying two stage snap action control.

Other objects will be in part obvious or pointed out in the following specification and claims, taken in view of the drawing, in which,

Fig. 1 is a front view of one form of my invention using slow action switches, and

Fig. 2 is a front view of a modification thereof, employing snap action switches.

Referring now in detail to the drawings, the reference character 10 designates a base. Upon the base 10 is a pivot 11 to which a bimetallic strip 12 is secured by means of a bracket 13. The bimetallic strip 12 is formed so as to provide the right and left legs thereof or the heat responsive control members 12a and 12b respectively. The bimetallic element 12 is freely pivoted on the pivot 11 and may rotate therearound under the influences of temperature variations, in a manner to be more fully pointed out herein-after. On the lower ends of the bimetallic element 12 are secured movable contact assemblies

generally indicated by the reference characters 15 and 16. The contact assembly 15 comprises two relatively stiff arms 17 and 18 having contacts thereon and a relatively flexible arm 19 having a contact on either side of the lower end thereof. The contact assembly 16 has two relatively stiff contact arms 20 and 21 having contacts thereon and a relatively flexible contact arm 22 having a contact on each side of its lower end.

Stationary contacts which cooperate with the movable contacts of the contact assembly 16 are the cold contacts 25 and 26, called cold contacts inasmuch as these contacts are engaged by the movable contacts when the thermostat is moving in cooling direction under the influence of falling temperature. When the bimetallic member 12 is heated, the hot contacts 27 and 28 are engaged by the movable contacts of the contact assembly 16. The stationary contacts 25, 26, 27, and 28 are suitably secured to brackets carried upon an insulating panel 29.

The stationary contacts for the contact assembly 15 are cold contacts 30 and 31 which are engaged by the movable contacts when the bimetallic member 12 is cooling. Also provided are hot contacts 32 and 33 which are engaged by the movable contacts when the bimetallic member 12 is heating.

The contacts 30, 31, 32 and 33 are suitably mounted on brackets carried by an insulating panel 35. This panel 35 is secured to an arm 36 which is pivotally mounted upon the pivot 11. A spring 37, which engages an ear 38 upon the arm 36 and an ear 39 that is struck up from the base 10, biases the arm 36 in a counter-clockwise direction. A cam surface 40 of the insulating panel 35 engages a cam 41 which is fixed to a rotary pivot 42. Also secured to the pivot 42 is an adjustment dial 43. The adjustment dial 43 has indicia 44 thereon which cooperate with a pointer 45, to indicate the control setting for the device.

A plurality of biasing springs 50, 51 and 52, the latter two of which are adjustable are provided to give the proper sequence of operation to the mechanism. The tension spring 50 is adapted to exert a biasing force tending to pivot the thermostatic element 12 in a counter-clockwise direction. Counteracting the biasing effect of the spring 50 are the expansion springs 51 and 52. The springs 51 and 52 are of the variable tension type so that the biasing force exerted thereby is increased as the springs 51 and 52 are compressed and decreased as the springs 51 and 52 expand. The latter springs 51 and 52 exert a biasing force tending to pivot the thermostatic element 12 in a clockwise direction and thereby tending to counteract the counter-clockwise biasing force of the tension spring 50. As shown in Figure 1

the biasing force of the spring 50 is balanced by the biasing force of the springs 51 and 52 when in the neutral position.

Upon a decrease in temperature the ends of bimetallic thermostatic element 12 will tend to spread apart. The outward warping of the element 12 will tend to compress the variable tension spring 52 so as to increase the tension exerted thereby on the right leg 12a of the element 12. Thereupon the combined tension exerted by the springs 51 and 52 in a clockwise direction will tend to exceed that of the tension spring 50 in a counter-clockwise direction causing a gradual pivoting of the element 12 in a clockwise direction tending towards balancing the biasing effects exerted by the spring elements 50, 51 and 52 as the thermostatic element 12 continues to warp outwardly until the clockwise movement of the element 12 is limited at the left leg 12b by the switch member 30 previously described.

Upon the limiting of the clockwise movement of the element 12 the right leg 12a of the element 12 will warp outwardly upon a further decrease in temperature until limited by the switch element 25.

Now with the element 12 in the latter position engaging the switch elements as described, upon an increase in temperature the legs 12a and 12b of the element 12 will tend to converge or warp inwardly so that the element 12 under the biasing force of the increased tension of the compressed spring 52 and spring 51 will be gradually pivoted clockwise on the pivot 11 against the tension of the spring 50. However since the left leg 12b of the element 12 is limited by the switch element 30 as previously noted the effect of such inward warping of the element 12 and biasing force of spring 52 will be to cause the right leg 12a of the element 12 to break from the switch element 25. Moreover as the increase in temperature continues the inward movement of the right leg 12a of the element 12 will reach a point where the tension exerted by the variable tension spring 52 will be decreased by the expansion thereof to such an extent that the combined force of the springs 51 and 52 will merely balance the positively directed tension force of the spring 50. Further inward warping of the element 12 will then cause the left leg 12b of the element 12 to break from the switch element 30 and cause the gradual counter-clockwise movement of the element 12 under tension of the spring 50 tending thereby to balance the tension forces exerted on the element 12 by the combined biasing force of the variable tension springs 51 and 52 until the element 12 is once again returned to the balanced neutral position indicated in Figure 1.

Upon a further increase in temperature the inward warping of the element 12 will continue causing an increase in the tension exerted on the left leg 12b of the element 12 by the variable tension spring 51 so that the combined force exerted by the springs 51 and 52 will tend to cause the gradual clockwise movement of the element 12 against the counter-clockwise biasing force of the spring 50 until the right leg 12a of the element 12 is limited by the switch element 27. Upon further increase in temperature the left leg 12b of the element 12 will be warped inwardly until limited in turn by the switch element 32. Such inward warping of the element 12 will compress the variable tension spring 51 causing an increase in the tension exerted thereby. Thus upon a decrease in the temperature the tension exerted by the variable tension spring

51 will exceed that exerted by the relatively expanded spring 52 so that upon the outward warping of the element 12 in response to a temperature decrease the left leg 12b of the element 12 will break first from the switch element 32.

Upon a further decrease in temperature the legs 12a and 12b of the element 12 will continue to gradually warp outwardly while the tension springs 51 and 52 will tend to pivot the element 12 in a clockwise direction on the pivot 11 against the limiting effect of the switch element 27 until a point is reached where the tension exerted by the variable tension spring 51 will be decreased by the expansion thereof so that the combined forces of the springs 51 and 52 will nearly balance the counteracting force of the tension spring 50. Further outward warping of the element 12 in response to a decrease in temperature will then cause the right leg 12a of the element 12 to break from the switch element 27 in response to the gradual counter-clockwise movement of the element 12 under the tension force exerted by the spring 50. Such tension will tend to position the element 12 so as to balance the tension forces exerted by the variable tension springs 51 and 52 and the tension spring 50. The element 12 will continue in a counter-clockwise direction as the temperature decreases until the same is positioned in the balanced or neutral position such as indicated in Figure 1.

The aforesigned sequence of operation of my invention is for the purposes which will be hereinafter fully pointed out in connection with the operation of the device.

Operation of Figure 1

The device is shown in its neutral position in the drawing of Figure 1, that is, none of the contacts are in engagement. Assume now that the temperature to which the thermostatic element 12 responds begins to decrease. Under a decreasing temperature the ends of the bimetal element 12 will tend to spread apart as hereinbefore explained. Hence, upon a cooling temperature the lower left hand leg of the bimetal will move toward the left to move the contact assembly 15 toward the stationary contacts 30 and 31. As is shown by the spacing of the contacts in the drawing, the contact carried by the flexible arm 19 will first engage the stationary contact 31. Upon a further decrease in temperature, the flexible arm 19 will be pressed back and the movable contact carried by the relatively stiff arm 17 will engage the contact 30. In a conventional control system, not shown, when the contact 31 was engaged no control function would be performed, but when the contact 30 has engaged its contact a relay or other device would be energized and a holding circuit for such device would be established through the stationary contact 31. Such control systems are well known in the art and therefore have not been disclosed as they do not form a particular part of the present invention.

As the temperature to which the bimetallic member 12 continues to decrease the legs of the bimetallic member will tend to spread further apart. Inasmuch as the stationary contact 30 has now been engaged by the contact carried by the relatively stiff member 17, the spring 52 will now be compressed by the cooling action on the bimetal. Hence, upon further cooling the stationary contact 26 at the opposite end of the bimetal will be engaged by the contact carried by the flexible contact arm 22. Upon still further

cooling of the bimetal the stationary contact 25 will be engaged by the contact on contact arm 21. Engagement of both stationary contacts 25 and 26 may energize a circuit for a control device similar to that pointed out hereinbefore.

In applying the present device to a two-stage heating operation, the stationary contacts 30 and 31 would control a system at a low stage of operation. In the event that this heating system were not sufficient to raise the temperature in the space to which the thermostatic 12 responds, then the thermostat would further cool and cause the stationary contacts 25 and 26 to engage. At this time, a larger capacity heater would be brought on which would cause the thermostat 12 to soon become satisfied.

When the system is operating on the cooling cycle, the action of the thermostat 12 is substantially the same as pointed out before in describing the heating operation. That is, as the thermostat 12 is subjected to higher temperature the ends of the bimetallic element 12 tend to move closer together. At this time the adjustable spring 51 resists movement of the left hand leg of the bimetal 12 but the lower right hand end thereof is free to move toward the left. As it moves toward the left the movable contacts of the structure 16 engage their respective stationary contacts 27 and 28 to energize a first stage cooling means. Upon further heating of the bimetallic element 12, the element will rotate upon the pivot 11 and the switch contact 27 to cause the element 12 to overcome the tension of spring 51 to cause the movable contacts on the arms 18 and 19 of the structure 15 to engage their respective stationary contacts 32 and 33. At this time a maximum capacity cooling means may be put into operation.

To adjust the device shown in Figure 1, the adjustment dial 43 may be rotated until the pointer 45 registers with the desired adjustment indicia 44. Upon rotating the dial 43 the cam 41 will likewise be rotated which will cause the insulating member 35 to be moved in one direction or the other to bodily position the stationary contacts 30, 31, 32 and 33. It will be obvious that when these contacts are positioned that the control setting of the device is changed inasmuch as the legs of the bimetallic element 12 will need to take a different position to cause the device to be in its neutral position.

Structure of Figure 2

Now the structure shown in Figure 2 will be described. The base 10 has a pivot 11 thereon to which the bimetallic member 12 is secured by the bracket 13. This structure is identical to the structure disclosed in Figure 1. Likewise, the adjustment structure comprising the rotatable pivot 42 having cam 41 and the adjustment dial 43 thereon are also identical. An adjustment arm 136 takes a slightly different form than the adjustment arm disclosed in Figure 1. The adjustment arm 136 has an ear 138 thereon which is connected to the tension spring 37 which is in turn connected to the stuck-up ear 39 on the base 10. The spring 37 biases the arm 136 so that the lower end thereof will engage the adjustment cam 41, not shown.

A plurality of snap action switches 60 and 70 control some suitable heating means, not shown. A plurality of switches 80 and 90 control a cooling means, not shown. The switches 70 and 90 are mounted upon the adjustment arm 136 and may be moved to vary the control setting for the

thermostatic element 12 in a manner similar to the operation of setting the control point described in connection with Figure 1.

- Each of the control switches 60, 70, 80 and 90 is similarly constructed. For this reason, only one of them will be described in detail. The switch 70 has a stationary contact 71 cooperable with a movable contact 72 that is carried upon an arm 73 which is pivoted at 14. A spring 75 biases the arm 73 toward the right at all times. A push button 76 engages the lower left hand end of the bimetallic element 12. The push button 76 is secured to a spring 77 which engages the inner side of a cup 78. When the lower left hand end of the bimetallic element 12 moves towards the left the spring 77 is compressed a sufficient amount to overcome the tension of the spring 75 at which time the arm 73 will begin to move toward the left. As is shown in the drawing as the arm 73 rotates towards the left the angle between it and the line of force exerted by the spring 75 will decrease. In the structure shown it is desired that the effective force exerted on the arm 73 by the spring 75 will decrease at a more rapid rate than the force stored up in the spring 77 to give a spring rate compensation snap action to the switch contact 72. It will be understood, however, that other snap action devices could be utilized.
- 30 The spring 75 of the switch 70 is of slightly lighter tension than the spring 65 of the switch 60. By such structure the switch 70 will be the first one to snap upon cooling movement of the bimetallic member 12, in a manner to be more fully described hereinafter. Similarly the spring 85 of the switch 80 is weaker than the spring 95 of the switch 90.

Operation of Figure 2

- 40 In response to a decrease in temperature the distal ends of the bimetallic member 12 will tend to spread apart. Upon spreading apart the lower right hand end will tend to snap the switch 60 and the lower left hand end will tend to snap the switch 70. However, because spring 65 of switch 60 is stronger than the spring 75 of switch 70 the bimetallic member 12 will bear against the snapping pin of the switch 60 and compress the spring 78 of switch 70 to such an extent that the switch 50 70 will snap and the contacts 71 and 72 will engage. Inasmuch as contacts 71 and 72 engage first these would accordingly be connected to a first stage conditioning means, not shown. Upon further cooling of the medium surrounding the 55 bimetallic member 12, the lower left hand end thereof would bear against the switch actuating pin 76 and rotate about the pivot 11 to cause the lower right hand leg of the switch to move toward the right and compress and actuate the switch 60. The switch 60 might control a maximum stage heating means.

When operating on the cooling cycle the operation of the device would be identical to that described in connection with heating. That is, 65 when the bimetallic member 12 is subjected to a rise in temperature the ends of the bimetallic member would tend to move toward each other. As they move toward each other the force exerted by the bimetal would act on the spring 95 of the switch 80 and spring 85 of the switch 80. Inasmuch as the spring 85 is weaker than the spring 95 the first switch to snap would be the switch 80. The switch 80 might bring on a minimum capacity cooling means. Upon further heating of the bimetal the bimetallic member 12

would bear upon the actuating pin for switch 80 and rotate around the pivot 11 to cause the switch 90 to be snapped. It will be understood that upon the bimetal cooling off and moving in the opposite direction just reverse of the above action will take place, that is, the switch 90 having the stronger spring 95 therein will be the first to snap off and the switch 80 having the weaker spring therein will be second to snap to off position.

While I have described two forms which my invention may take it will be clearly understood that those skilled in the art will devise many modifications thereof. For example, it would be obvious to substitute magnetic snap action switches for my spring rate compensated snap action switches, or to substitute over-center snap action switches. Also, in connection with that type of structure shown in Figure 1 it would be obvious to eliminate certain of the contacts, or to add more contacts thereto if desired. Likewise it will be obvious to those skilled in the art to employ the present device to control pneumatic systems, valves, and the like. For this reason I wish not to be limited in my invention only to those forms shown and described but by the spirit and scope of the appended claims.

I claim as my invention:

1. In an apparatus of the character described, comprising in combination, thermostatic means including first and second portions, each of the portions being movable in a first sense upon heating and in a second sense upon cooling, first control means actuated by the first portion as it moves in the first sense, second control means actuated by the second portion as it moves in the first sense, third control means actuated by the second portion as it moves in the second sense and fourth control means actuated by the first portion as it moves in the second sense, and means for actuating said thermostatic means so as to cause the return of said portions to a neutral position at a predetermined temperature.

2. A control device comprising in combination, a base, a pivot on said base, an elongated bimetal strip pivotally mounted at a point between its ends upon said pivot, said strip being movable in a first sense upon heating and in a second sense upon cooling, first and second electrical contacts actuated by said strip as it moves in said first sense, third and fourth electrical contacts actuated thereafter by said strip as it continues to move in said first sense, fifth and sixth electrical contacts actuated by said strip as it moves in said second sense, and seventh and eighth electrical contacts actuated thereafter by said strip as it continues to move in said second sense.

3. A control device comprising in combination a base, a pivot on said base, a variable condition responsive control member pivotally mounted at a point between its ends upon said pivot, the said control member being movable in a first sense upon heating and in a second sense upon cooling, first and second electric contact means actuated by the said control member as it moves in said first sense, and third and fourth electric contact means actuated by the said control member as it moves in said second sense, and first resilient means associated with said control member for causing said first contact means to be actuated prior to said second contact means, and second resilient means associated with said control member for causing said third contact means to be actuated prior to said fourth contact means.

4. A control device comprising in combina-

tion a base, a pivot on said base, a variable condition responsive control member pivotally mounted at a point between its ends upon said pivot, the said control member being movable in a first sense upon heating and in a second sense upon cooling, first and second electric contact means actuated by the said control member as it moves in said first sense, and third and fourth electric contact means actuated by the said control member as it moves in said second sense, and first resilient means associated with said control member for causing said first contact means to be actuated prior to said second contact means, second resilient means associated with said control member for causing said third contact means to be actuated prior to said fourth contact means, and a third resilient means associated with said control member for returning the said control member to a neutral position at a predetermined tempera-

ture.

5. A control device comprising in combination, a base, a pivot on said base, an elongated bimetal strip pivotally mounted at a point between its ends upon said pivot, said strip being movable in a first sense upon heating and in a second sense upon cooling, a first snap action device actuated by said strip as it moves in said first sense, a second snap action device actuated thereafter as said strip continues to move in said first sense, a third snap action device actuated as said strip moves in said second sense, and a fourth snap action device actuated thereafter as said strip continues to move in said second sense.

6. A control device comprising in combination, a base, a pivot on said base, an elongated bimetal strip pivotally mounted at a point between its ends upon said pivot, said strip being movable in a first sense upon heating and in a second sense upon cooling, a plurality of pairs of snap action switching means adjacent the ends of said strip, relatively weak spring means associated with one pair of said switching means, and relatively strong spring means associated with a second pair of said switch means, said strip bearing upon one of said stronger springs and rotating upon said pivot to overcome one of said weaker springs to provide a first stage snap action and rotating upon said pivot while bearing upon the contacts associated with said weaker spring to overcome the force of said stronger spring to provide a second stage snap action, as the strip moves in either of its senses.

7. In an apparatus of the character described, comprising, in combination, heat responsive means including first and second portions, each of the portions being movable in a first sense upon heating and in a second sense upon cooling, first control means actuated by the first portion as it moves in the first sense, second control means actuated by the second portion as it moves in the first sense at a temperature above the temperture at which the said first control means is actuated, third control means actuated by the second portion as it moves in the second sense, fourth control means actuated by the first portion as it moves in the second sense at a temperature below the temperature at which the said third control means is actuated, and biasing means for preventing the actuation of the fourth control means upon the second portion actuating the third control means.

8. In an apparatus of the character described, comprising, in combination, heat responsive means including first and second portions, each of the portions being movable in a first sense upon heating and in a second sense upon cooling, first control means actuated by the first portion as it moves in the first sense, second control means actuated by the second portion as it moves in the first sense at a temperature above the temperature at which the said first control means is actuated, third control means actuated by the second portion as it moves in the second sense, fourth control means actuated by the first portion as it moves in the second sense at a temperature below the temperature at which the said third control means is actuated, and biasing means for preventing the actuation of the second control means upon the first portion actuating the first control means.

9. In an apparatus of the character described, comprising, in combination, heat responsive means including first and second portions, each of the portions being movable in a first sense upon heating and in a second sense upon cooling, first control means actuated by the first portion as it moves in the first sense, second control means actuated by the second portion as it moves in the first sense at a temperature above the temperature at which the said first control means is actuated, then third control means actuated by the second portion as it moves in the second sense, fourth control means actuated by the first portion as it moves in the second sense at a temperature below the temperature at which the said third control means is actuated, and biasing means actuating the heat responsive means in such a manner as to return said portions thereof to a neutral position at a predetermined temperature.

10. In combination, a freely pivoted distortable thermal means having two spaced movable portions, each of the said portions of the thermal means being movable in a first sense upon heating and in a second sense upon cooling, control means engaged by the said portions of the thermal means as the said portions move in the first sense, and other control means engaged by the said portions of the thermal means as the said portions move in the second sense.

11. In combination, a freely pivoted distortable thermal means having two spaced movable portions, each of the said portions of the thermal means being movable in a first sense upon heating and in a second sense upon cooling, control means engaged by the said portions of the thermal means as the said portions move in the first sense and other control means engaged by the said portions of the thermal means as the said portions move in the second sense, and tension means whereby the said portions of the thermal means are positioned in such a manner as to disengage all of the said control means at a predetermined temperature.

12. In combination, a base, an expansible member mounted thereon in a manner to permit movement of each end of said member upon expansive and contractive movements thereof, a first pair of devices of which one is operated by each end of said member upon expansive movement of said member, a second pair of devices of which one is operated by each end of said member upon contractive movement of said member, one of each of said pairs of devices acting as a means to constrain further movement of that end of the member which operates it so

that further movement of said member is imparted solely to the other end thereof so as to operate the other of said pair of devices.

13. In combination, a base, an expansible member mounted thereon in a manner to permit movement of each end of said member upon expansive and contractive movements thereof, a first pair of devices of which one is operated by each end of said member upon expansive movement of said member, a second pair of devices of which one is operated by each end of said member upon contractive movement of said member, means to constrain expansive movement of one end of said member so that the other end thereof moves first to operate its one of the first pair of devices after which the second of said first pair of devices is operated by the other end of said member upon further expansive movement thereof, and means to constrain the contractive movement of one end of said member so that the other end thereof moves first to operate its one of the second pair of devices after which the second of said second pair of devices is operated by the other end of said member upon further contractive movement thereof.

14. In an apparatus of the character described, comprising, in combination, heat responsive means including first and second portions, each of the portions being movable in a first sense upon heating and in a second sense upon cooling, first control means actuated by the first portion as it moves in the first sense, second control means actuated by the second portion as it moves in the first sense at a temperature above the temperature at which the said first control means is actuated, third control means actuated by the second portion as it moves in the second sense, fourth control means actuated by the first portion as it moves in the second sense at a temperature below the temperature at which the said third control means is actuated, biasing means for preventing the actuation of the second control means upon the first portion actuating the first control means, biasing means for preventing the actuation of the fourth control means upon the second portion actuating the third control means, and biasing means actuating the heat responsive means in such a manner as to return said portions thereof to a neutral position at a predetermined temperature.

15. In an apparatus of the character described, comprising, in combination, heat responsive means including first and second portions, each of the portions being movable in a first sense upon heating and in a second sense upon cooling, first control means actuated by said first portion as it moves in the first sense, second control means actuated by the second portion as it moves in the first sense at a temperature above the temperature at which the said first control means is actuated, third control means actuated by the second portion as it moves in the second sense, fourth control means actuated by the first portion as it moves in the second sense at a temperature below the temperature at which the said third control means is actuated, biasing means for preventing the actuation of the second control means upon the first portion actuating the first control means, and biasing means for preventing the actuation of the fourth control means upon the second portion actuating the third control means.

GIFFORD I. HOLMES.
